UNITED STATES PATENT OFFICE.

EDGAR ARTHUR ASHCROFT, OF LONDON, ENGLAND.

APPARATUS FOR THE ELECTROLYTIC MANUFACTURE OF ALLOYS OF LIGHT METALS WITH HEAVIER METALS AND THE CONTINUOUS TREATMENT OF SUCH ALLOYS FOR OBTAINING FINAL PRODUCTS.

1,159,154.

Specification of Letters Patent.

Patented Nov. 2, 1915.

Application filed March 12, 1912. Serial No. 683,375.

To all whom it may concern:

Be it known that I, EDGAR ARTHUR ASHCROFT, a subject of the King of Great Britain and Ireland, and residing at 99 Buckingham Palace road, in the county of London, England, and at Sande Gaard, Balestrand, Sogn, Norway, electrochemical engineer, have invented new and useful Improvements in an apparatus for the electrolytic manufacture of alloys of light metals with heavier metals and the continuous treatment of such alloys for obtaining final products, of which the following is a specification.

The object of my invention is to effect in a very efficient manner the manufacture of alloys of light metals (particularly alkali metals) with heavier metals, such, for instance, as sodium with lead by the electrolysis of fused salts of light metals and the simultaneous production of anode products in a very pure condition, and also the continuous treatment of alloys such as those aforesaid for obtaining final products.

My invention relates more particularly to processes in which a salt of an alkali metal (or a mixture of such salts) is electrolyzed in a first cell over a cathode of molten lead, or alloy, the resulting alloy of the alkali metal and lead being then passed, or removed, from the first cell to a second cell and returned again and so on continuously. The most important products obtainable by this means are the amids, cyanamids, cyanids, and hydrates of the alkali metals, or the alkali metals themselves, or their peroxids, but other metals, such as calcium, lithium, and their derived products, may also be similarly produced.

My invention relates particularly to means for obtaining only one metal, or metal compound, (for instance sodium or a compound thereof) as a final product while still obtaining the advantages which are known to accrue from using certain other metal salts in admixture in the electrolyte of the first cell, namely a lower fusing point and higher current efficiency; also to the obtainment of the anode product (for example gaseous chlorin) in more concentrated form, as well as to improvements in apparatus whereby certain well known difficulties are avoided and the several steps of the process are rendered more practical and are cheapened.

I will describe the process as applied to

the production of sodium-lead alloys from fused sodium chlorid in admixture with fused potassium chlorid, from which its other applications will also be understood.

It is well known that it is extremely difficult and in fact commercially impracticable to electrolyze pure fused sodium chlorid alone, because high current efficiency and stable electrolysis cannot be obtained in the first cell if sodium chlorid be present alone. It is also known that a mixture of sodium and potassium chlorids, in about molecular proportions, fuses at such a comparatively low temperature (670° centigrade) that the current efficiency is high and the electrolysis is stable but hitherto, under such conditions, metallic potassium in considerable quantities has always been deposited with the metallic sodium into the alloy and tends to pass into the final product. The presence of the potassium in the product as well as the consumption of the more costly potassium salt required to supply it have hitherto been objectionable features in such processes. I have found that by observing the herein-after explained conditions it is possible to use such a mixture of salts in the first cell and to obtain in the second cell metallic sodium alloy containing practically no metallic potassium, or but little metallic potassium.

For brevity of description I will presume that a mixture of sodium chlorid and of potassium chlorid is fused in the first cell and that metallic sodium is to be produced in the second cell, but my invention is not limited to the use of sodium chlorid and potassium chlorid, nor to the production of metallic sodium. In using all such fused mixtures in contact with fused alloys I have found that reversible reactions occur at the place of contact of the electrolyte with the alloy in the first cell, at the place of contact of the alloy with the electrolyte, or reacting body, in the second cell, and also (when metals are produced) at the place of contact of the produced alkali metal with the electrolyte in the second cell. All these reversible reactions occur at each place to an extent in accordance with the proportions of the several metallic elements in the alloy and in the fused salts respectively, and in all cases are promoted by agitation.

In the case of admixtures of sodium and

potassium salts by reason of the greater combining energy of the potassium base, it is found that although considerable quantities of potassium are, in the first instance, carried into the alloy by reason of the excessive current density which must be employed in all such apparatus, in order to maintain the required temperature, yet, when the apparatus is suitably arranged and proportioned, the said reverse reactions tend thereafter rapidly to increase the proportion of metallic sodium and to reduce the proportion of metallic potassium in the final product as herein explained. The conditions necessary for obtaining the desired result according to my invention are the maintenance of a suitable proportion of the salts of the two metals and the alloys of these metals in the respective parts of the apparatus, particularly at the aforesaid places of reversible reactions, and a somewhat rapid circulation of the alloy and of the supernatant fused salts in the respective cells, and particularly a somewhat rapid and continuous agitation of the electrolyte in the first cell in order to promote the described reversible reactions and of the fused body in the second cell.

The reversible reactions referred to are found to proceed in either direction according to the percentages of the respective metal salts, or metals, present in the melts and in the alloys. A typical reaction of this class taking place in the second cell is the following:

If, in proportion to the sodium present in each case, much potassium be present in the alloy and but little in the supernatant melt, an interchange will take place whereby sodium is substituted for potassium in the alloy or vice versa, and these changes will proceed until a balance, or equilibrium, has been reached according to well known physical and chemical laws. By this means therefore it is possible as aforesaid to reduce the final potassium content of the product to none at all or to very small percentages; moreover in the first cell the typical reaction

although reversible like the others and proceeding only until equilibrium is attained is far more powerful in one direction than in the reverse direction, so that if freshly melted and continually renewed sodium chlorid be employed to react on the triple alloy in a separate receptacle before removing the sodium, it is possible to extract all or practically all of the potassium from the alloy, substituting sodium therefor and simultaneously to regenerate the potassium

chlorid required for use in the first cell. This will in some cases present considerable economical advantages. The procedure in that case is as follows: The sodium chlorid which is to form the raw material for the electrolysis is first melted (preferably in a vessel heated internally by the electric current, the contents being also preferably agitated, or caused to rotate, by the same agent) in contact with the alloy containing both sodium and potassium which has just been produced in the first cell. The fresh salt extracts the potassium from the alloy and then passes to the first cell (containing a useful admixture of potassium chlorid) preferably while still in a melted condition, while the alloy now free or practically free from potassium, passes off to the second cell.

I have found by experiment that by observing the aforesaid conditions and operating as described, the first cell may contain for example a mixture of 40 per cent. of sodium chlorid and 60 per cent. of potassium chlorid, which mixture insures a minimum fusing point (670° centigrade) and a very efficient and stable electrolysis, and under the conditions aforesaid metallic sodium containing less than one per cent. of metallic potassium can be obtained from the second cell and other derivatives can be obtained in a corresponding state of freedom from metallic potassium. In most cases however in practice this "triple" procedure will not be required and it will be sufficient by the hereinafter described means whereby the electrolyte in the first cell is maintained in continuous motion relatively to the underlying alloy to effect the desired object to a sufficient degree of completeness while at the same time securing a rich and concentrated anion product. According to this preferred mode of carrying out my invention the first cell is provided with means for passing an electric current (preferably the main current) once of more than once around the cell so as to create a magnetic field and so cause a constant whirling of the fused salt and a simultaneous stirring or agitation of the alloy, so that the bulk of the gaseous anion is projected toward the center of the cell where there is a hollow anode through which the pure gas is led off for utilization for any purpose where undiluted gas is required, while the aforesaid reversible reactions are promoted to a considerable extent. The portion of the cell outside the anode may remain open and under a sufficient current of air to carry off (preferably for separate utilization) the small proportion of the gaseous anion which is given off at the periphery of the anode. The anode is preferably made of a graphite cylinder and is built up of uniform segmental longitudinal pieces fitted together, the interior of the cylinder being preferably large enough to 125

allow in case of need of access to the cell when the central loose cover of the anode is removed.

The electrical contact with each segment of the cylinder can be effected by providing a metallic cap for the whole and separately securing each segment with a bronze or copper bolt having an extended point dipping into a molten lead contact. A special device which may be employed for preventing the attack of air on the exposed outer surface of the graphite cylinder consists in a recess in the graphite cylinder extending from just below the electrolyte to a few centimeters above it and filled with refractory material which is confined in place by a sleeve of enameled iron or the like. Suitable pipe connections are provided for leading off the rich and also the less concentrated gases from the cell to separate destinations. To maintain the balance of the two metals in the apparatus during the continuous process on these principles, an amount of potassium chlorid corresponding to that of the potassium which may be found in the final product of the second cell should be fed into the first cell together with the sodium chlorid. The amount required will be much less than heretofore and may usually be less than $2\frac{1}{2}$ per cent. Other metallic salts may be used in admixture with the principal salts, the metal of the diluting salt being eliminated by the reversible reactions referred to, for I have found that reversible reactions also occur with salts of such metals. Such other salts may for example be salts of barium, strontium, calcium, lithium and the like.

Another feature of this invention is the employment of an intermediate receptacle for the reception and storage of the fused alloy in its passage between the two cells and of weirs or overflows to the two cells for maintaining a constant working level, also the provision of very simple devices for effecting the circulation of the alloy between the respective parts of the apparatus. In the preferred construction all these objects are secured and practical difficulties hitherto encountered in confining the alloy are completely overcome by the use of a single casting preferably of steel as the under part of the apparatus, as hereinafter more fully described.

I have found that in order to maintain in both the first cell and the second cell the constant level of alloy surface which is essential to the maintenance of uniform and efficient electrolysis, or other reactions, in the cells, as well as to insure an even flow of the alloy from the first cell to the second cell and the regular return of the depleted alloy, which are also essential to successful working, the channels of communication between the cells may very advantageously

be provided with an intermediate receptacle placed preferably in the path of the alloy leaving the first cell, which receptacle will allow of considerable changes of bulk in the total circulating alloy (which changes take place on any change in the proportion of alkali metal which it contains) without affecting either the constant level in either of the cells, or the even flow from cell to cell.

The fused alloy preferably passes over a suitable weir or fixed level overflow from the first cell into the said receptacle and passes, or is pumped, therefrom (by a rotating worm or by an ordinary pump for example) into the second cell, there being a passage from the second cell provided also with a weir or the like (which is preferably inside the said cell) by which the depleted metal passes back to the first cell thus completing the cycle. It is desirable also to provide a comparatively thin refractory lining of heat insulating (basic) material inside the first cell so that the alloy in contact therewith at a high temperature shall not too rapidly lose its heat to the casting and to the surrounding alloy which will be maintained at a lower temperature by external heating.

The construction which I prefer is illustrated in the accompanying drawings.

Figure 1 is a sectional elevation and Fig. 2 is a plan of the whole apparatus; both figures showing also details of the first and second cells and the special anode. Fig. 3 is a sectional elevation (taken on the line A, B, Fig. 4) and Fig. 4 is a plan of the main casting constituting the base of the apparatus including the alloy reservoir and circulating passages and weirs. Figs. 5, 6 and 7 are sections through the main casting, the said sections being respectively taken on the lines C, D, E, F, and G, H, and Fig. 8 is a vertical section through the vessel in which the raw material for the electrolysis is first melted.

In all the figures like reference numerals represent like parts.

The casting 3 (preferably of steel) has two circular cells constituting the lower or alloy-containing portion of the first and second cells 1 and 2 respectively as well as the reservoir or receptacle and the channels of communication 5, 6, 7 and 8. There is a lining 4 of refractory (basic) material for the inner part of the first cell 1. The alloy passages 5, 6, 7 and 8 widen out and also constitute the reservoir or storage receptacle for the working alloy. Weirs 9 and 10 are provided over which the alloy flows from the respective cells wherein the level is maintained constant. The weir in the second cell is placed within the cell and on either side of the circulating pump. Any suitable pump such as rotating worm pumps 11 and 19 may be employed for the circulation of

95

100

110

115

120

125

130

the alloy and electrolyte respectively. The upper portions of the first and second cells are bolted to the steel casting 3. The aforesaid composite graphite anode 12 is provided with the necessary electrical connections 13 and with protective devices consisting of a sleeve 14 of refractory material just entering the electrolyte and above it a sleeve 15 of enameled iron or other suitable material. There is an outlet 16 for rich anode gas and larger outlet openings and pipes 17 for the exterior gases through which also a current of air is continually drawn to avoid escape of any gases into the operating room. The second cell 2 like the first cell 1 is bolted to the steel casting 3. The construction of the second cell may be different in each case according to the particular product which is to be manufactured from the alloys. A copper conductor 18 of large cross-section gives rise to the magnetic field. A resistance coil 24 is arranged below the main casting Fig. 1, by means of which the under and outer parts and reservoir of the apparatus, together with the second cell and the metal outer container of the first cell, can be maintained at a constant temperature which will be approximately that of the second cell. I prefer to heat the apparatus as aforesaid by the application of an alternating heating current to the aforesaid coil 24, which is supported by the well insulated masonry base of the apparatus.

25 are beams upon which the apparatus is supported. The desired product, or, if the produced or dissolved metal be reacted *in situ*, then the derived product, can be removed by the pipe 26 and collected in the receiver 27 having an inspection device 28. From the receiver the product passes by the pipe 29 to the mold 30 which can be removed as and when desired. The cathode in the cell 2 is preferably constituted by small rods 31 of about 10 millimeters diameter carried by a plate 32 (preferably of copper) supported by tubes 33, or otherwise, the said tubes being carried on brackets 34. The aforesaid tubes 33 carrying the plate 32 can be adjusted to regulate the distance of the cathode from the anode and the extent of surface in contact with the electrolyte. The small rods 31 are preferably arranged in circumferential rows. The product overflows the weir 35 and floats on the electrolyte and remains in the upper part of the collecting chamber 36, being there conveniently aggregated into a floating mass, while the associated electrolyte falls to the bottom of the said receptacle, or chamber, and, by means of the passages 37, 38, passes to the pump 19, by which it is restored to the reservoir formed by the passages 5, 5^a, 6, 7 and 8.

The action of the apparatus is as follows: Either by artificial heat (preferably by the separate application of an alternating heat-

ing current to a resistor in the well insulated masonry base of the apparatus) or by its own internal electrically produced heat, the under and outer part and reservoir of the apparatus together with the second cell and the metal outer container of the first cell may be maintained at a constant temperature which will be approximately that of the second cell, namely from 300° to 500° centigrade, according to the secondary reactions to be carried on there, or the electrolyte in use, the lower temperatures being suitable for an amid, or a caustic electrolyte, or reactive body, and the higher temperatures for cyanid. The action of the current will, with the aid of the insulating lining, maintain the metal in the first cell in a much higher temperature (namely about 750° centigrade) which is suitable for the melting and freely circulating conditions of the fused salt electrolyte.

When the pump 11 is set in motion the flow of the alloy is as follows: From the passages 5 it is delivered by the aforesaid pump into the body of the second cell 2 over the top of the pump casing and flows to the other side of the said cell 2 and over the weir 10 and thence through the opening 10^a into the passage 5^a and through the opening 4^a into the cell 1. From here the alloy flows through the opening 6 and out over the weir 9 into the general reservoir constituted by the passages 5, 6, 7 and 8.

The advantages of this construction are many. The intermediate reservoir provides flexibility in bulk of the alloy so that when the alloy becomes too poor in alkali metal, shrinkage of bulk only occurs in the intermediate reservoir and not in the cells, and therefore the working of the process is not disturbed thereby. The disposition of the reservoir and passages around and between the respective cells as shown also provides an admirably graded temperature slope between the hotter and colder parts of the apparatus and enables separate electrical or other heat to be applied to the apparatus in the most simple and efficient manner. The entire outer part of the apparatus is worked at a uniform low temperature which insures great stability and durability to the casting constituting its principal part.

When the process is carried on as above suggested with a separate receptacle in which the triple alloy is reacted on by freshly melted and continuously renewed sodium chlorid, the additional vessel may be such as shown in Fig. 8. The sodium chlorid which is to form the raw material for the electrolysis is first melted in a separate vessel 20, Fig. 8, which is heated internally by the electric current supplied to the electrodes 21, 22, the contents of the vessel 20 being preferably agitated or caused to rotate by the influence of an electric current

passing through the coil 23 contained within a magnetic steel casing 44. The sodium chlorid is preferably melted in contact with the alloy containing both sodium and potassium which has just been produced in the first cell.

I do not confine myself to the precise construction of apparatus described and illustrated for it will be readily understood that many modifications may be made without departing from the nature of this invention. For example in place of the alloy reservoir being embodied in the main casting as shown, a separate kettle connected by suitable pipes and passages may be employed for the same purpose.

The further reactions of the alloys produced as aforesaid may be carried on in the second cell 2 according to any known or suitable methods but preferably as described in my copending applications Serial Numbers 683,376; 683,377 and 683,378 of even date herewith.

What I claim is:—

25 1. Electrolytic apparatus of the character described, comprising two cells adapted to maintain a body of alloy at constant level therein, a passage between said cells, an intermediate reservoir to take up variations in the bulk of the body of the alloy and means separating said reservoir from each of said cells, substantially as described.

30 2. Electrolytic apparatus of the character described, comprising two communicating cells adapted to maintain a body of alloy at constant level therein and supernatant electrolytes of different characters in the respective cells, having reversible reactions with the alloy therein, and means in the first cell, for agitating the electrolyte therein to facilitate the said reversible reactions between the primary electrolyte and the alloy in said cell, substantially as described.

35 3. Electrolytic apparatus of the character described, comprising two communicating cells adapted to maintain a body of alloy at constant level therein, in combination with an intermediate reservoir to take up variations in the bulk of the body of the alloy, together with means surrounding the first cell for setting up a magnetic field therein to cause a rotary motion in the alloy, for the purpose described.

40 55 4. Electrolytic apparatus of the character described, comprising two communicat-

ing cells adapted to maintain a body of alloy at constant level therein and supernatant electrolytes of different characters, having reversible reactions with the alloy, and means surrounding the first cell and in the interior of the casing thereof, for agitating the electrolyte therein to facilitate the said reversible reactions between the electrolyte and the alloy in said cell, substantially as described.

5. Electrolytic apparatus of the character described, comprising two communicating cells adapted to maintain a body of alloy at constant level therein, in combination with an intermediate reservoir to take up variations in the bulk of the body of the alloy, together with a hollow anode in the first cell for controlling the gaseous anode product of said cell and means for drawing off said product in a pure condition without completely closing the cell.

6. Electrolytic apparatus of the character described, comprising two communicating cells adapted to maintain a body of alloy at constant level therein, in combination with an intermediate reservoir to take up variations in the bulk of the body of the alloy, together with a hollow anode comprising a series of radially arranged segments forming a cylinder and provided with contacts and protecting devices, substantially as described.

7. Electrolytic apparatus of the character described, comprising two cells adapted to maintain a body of alloy at constant level therein, a passage between said cells, an intermediate reservoir to take up variations in the bulk of the body of the alloy, and means separating said reservoir from each of said cells, and a refractory heat insulating lining in the lower portion of the first cell, for the purpose described.

8. Electrolytic apparatus of the type described, comprising an integral casting forming the base thereof and comprising the lower portions of two cells, an intermediate reservoir, connecting passages between the cells and reservoir and weirs in said passages, substantially as described.

In testimony whereof I have signed my name to this specification in the presence of two subscribing witnesses.
